(57) **CLAIM**

The ornamental design for a watch dial, as shown and described.

DESCRIPTION

FIG. 1 is a left front perspective view of a first embodiment of a watch dial, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a right front perspective view thereof;

FIG. 9 is a left front perspective view of a second embodiment of a watch dial, showing my new design;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is a right front perspective view thereof.

The broken lines shown in the figures illustrate portions of the watch dial that form no part of the claimed design.

The figures include surface shading, which represents contour and not surface ornamentation.

1 Claim, 12 Drawing Sheets
